UNITED STATES PATENT OFFICE.

BENJAMIN ADELSON, OF CLEVELAND, OHIO.

WINDOW-SASH LOCK.

1,159,636.

Specification of Letters Patent.

Patented Nov. 9, 1915.

Application filed November 9, 1914. Serial No. 870,952.

To all whom it may concern:

Be it known that I, BENJAMIN ADELSON, a citizen of the United States, residing at Cleveland, in the county of Cuyahoga and 5 State of Ohio, have invented certain new and useful Improvements in Window-Sash Locks, of which the following is a specification.

My invention relates to improvements in 10 window sash locks, and more particularly to that class or type known as "ventilating sash locks," that is to say,—a lock which is adapted to lock the upper or the lower sash of a window, or both the upper and lower 15 sash of a window, when in a partially open position for the purposes of ventilation.

The primary object of my invention is to 20 provide a generally improved sash fastener or lock of this class, which will be exceedingly simple in construction, cheap of manufacture, efficient in use, and which may be readily and quickly attached to and detached from any ordinary window sash without the use of screws, nails, or other 25 attaching elements, and also without the use of any tools in the application of the improved fastener or lock.

A further object is the provision of a lock or fastener of this class which may be carried 30 in the pocket or hand bag of a traveler for ready application to both the upper and lower sash of an ordinary window for locking such sash as against further opening movement when either in a fully closed or 35 partially closed position.

A still further object is the provision of a lock or fastener of this class which will effectively coöperate with and lock the upper and lower sash in any adjusted position 40 without in any way marring or injuring the same while in use, as well as one which will in no way interfere with the free movement of either or both sash members to closed position without first moving or readjusting 45 the lock or fastener.

With the above mentioned and other ends in view, the invention consists in the novel construction, arrangement, and combination of parts, hereinafter described, illustrated 50 in one of its embodiments in the accompanying drawings, and particularly pointed out in the appended claims.

Referring to the drawings, forming a part of this specification, Figure 1, is a perspective view of the improved ventilating sash lock or fastener in its operative position ap-

plied to the upper and lower left hand corners of the lower and upper sash members respectively, of a window, the sash members of the window being in a partially open 30 position for the purposes of ventilation. Fig. 2, a vertical sectional view of such sash members the improved lock or fastener being applied to the right hand side thereof.

Similar numerals of reference designate 65 like parts throughout all the figures of the drawings.

The improved lock or fastener comprises a main base plate or support 1, terminating in a vertically extending portion 1^a, the latter being adapted to be interposed between the rear upper portion of the lower sash 2, and the adjacent lower front or face side of the upper sash 3, it being apparent that the parts 1, and 1^a, are bent at an angle to conform to the form or contour of the upper portion of the lower sash and that the depending or anchor portion 1^a, is adapted to prevent any longitudinal movement of the plate or support 1, when the locking or 80 latching member hereinafter described is brought into coöperative locking engagement with the upper sash.

As a means of locking the sash members 2, and 3, in any desired adjusted or opened 85 position as against further opening movements, the base plate or support 1, is provided with hinge lugs 1^b, carrying a hingedly or pivotally mounted lever or locking member 4, the free end of said locking 90 member being adapted to come into engagement with the inner lower face side of the upper sash 3, so that the locking member 4, will have a toggle like gripping action to prevent any further relative or opening 95 movements of either or both of the two sash members in an obvious and well understood manner.

If desired, the free end of the locking or lever member 4, may be provided with an 100 outwardly flaring or conical shaped recess 4^a, to receive and contain a similarly shaped resilient gripping member 4^b, such as rubber, cork, or the like.

It will be observed that the lever member 105 4, is formed of a single blank of sheet metal and is crimped longitudinally of its length to form the vertically extending sides of the shank portion thereof to reinforce and strengthen said shank portion, one end of 110 said lever being bent or curled about to form a hinge lug interposed between the

hinge lugs 1^b, of the base plate, the outer or free end of said lever being formed into a conical shaped split head (see Fig. 2) forming the outwardly flaring or conical shaped recess 4^a, to receive and contain the similarly shaped resilient gripping member 4^b, the latter being securely retained in the socket by being securely engaged by the split head crimped or formed about the same. It will also be observed that the locking or lever member 4, in the present instance, comprises a single piece of metal bent into vertically extending sides to form the shank portion thereof and also bent at one end to form an outwardly flaring or conical shaped head 4^a, to form a similarly shaped recess for receiving the similarly shaped resilient grip member 4^b, the opposite end of the locking or lever member 4, being bent or curled about to form a hinge lug interposed between the upwardly and rearwardly extending hinge lugs 1^b, of the base plate or support 1.

It will be apparent that the form and relative position of the toggle acting lever or locking member 4, is such with respect to the sash members and the relative movements of the latter that such sash members will be securely locked as against further opening movements in any desired adjusted positions and that either or both of said sash members may be moved to or toward closed positions without any further attention to the toggle acting or locking member 4, the free end of the latter being adapted to freely slide against the face side of the upper sash while either or both of said sash members are being moved toward closed position.

From the foregoing description, taken in connection with the accompanying drawings, the operation and advantages of my invention will be readily understood.

Having thus described one of the embodiments of my invention, what I claim and desire to secure by Letters Patent, is,—

1. In a sash lock, a lever member comprising a single blank of sheet metal crimped longitudinally of its length and terminating at one end in an outwardly flaring conical shaped split head forming a similarly shaped conical shaped socket, and a similarly shaped sash engaging resilient member fitted in said socket and engaged by said split head.

2. In a sash lock, a lever member comprising a single blank of sheet metal bent longitudinally of its length to form vertically extending reinforcing sides and terminating at one end in a downwardly and inwardly curved hinge lug and at the other in a split head forming a socket, and a conical shaped

upper sash engaging resilient member fitted in said socket and engaged by said split head.

3. In a sash lock, the combination with the upper and lower sash members of a window, and a removably mounted supporting plate provided at one edge with a depending sash engaging anchor plate interposed between the rear portion of said lower sash member and the lower face side of said upper sash member and at the other with upwardly and inwardly curved hinge lugs; of an upwardly and rearwardly extending overhanging lever comprising a single blank of sheet metal bent longitudinally into vertically extending sides to form the shank portion thereof, and into a hinge lug at one end interposed between said hinge lugs of said supporting plate, the outer end of said lever terminating in a conical shaped split head forming a similarly shaped recess or socket, and a resilient conical shaped sash gripping member fitted in said socket and engaged by said split head, said resilient sash gripping member being arranged above said anchor portion to ride upon and engage with the face side of said upper sash member upon the relative opening movements of either or both of said sash members.

4. In a sash lock, a removable supporting plate bent at one end into a depending sash engaging anchor portion adapted to be interposed between the rear upper portion of the lower sash and the lower face side of the upper sash, said supporting plate terminating at its opposite or rear edge in upwardly and inwardly curved hinge lugs, a lever member comprising a single blank of sheet metal crimped longitudinally of its length and also bent into a hinge lug interposed between said hinge lugs of said base plate, said lever member overhanging said supporting plate and being bent at its free end into an outwardly flaring conical shaped split head forming a similarly shaped conical shaped socket, and a conical shaped resilient member fitted in said conical shaped socket and engaged by said split head, said resilient member normally projecting above said anchor portion in engagement with the face side of said upper sash whereby a locking action is imparted between said sash and lever members upon the relative movements of the same.

In testimony whereof I have affixed my signature in presence of two witnesses.

BENJAMIN ADELSON.
